US00D881161S

(12) **United States Design Patent** (10) **Patent No.:** **US D881,161 S**
Chen (45) **Date of Patent:** **** Apr. 14, 2020**

(54) **SPEAKER WITH INDUCTION CELL PHONE CHARGER**

(71) Applicant: **Pengcheng Chen**, Guangdong (CN)

(72) Inventor: **Pengcheng Chen**, Guangdong (CN)

(**) Term: **15 Years**

(21) Appl. No.: **29/644,485**

(22) Filed: **Apr. 18, 2018**

(51) LOC (12) Cl. **14-01**

(52) U.S. Cl.

USPC **D14/216**

(58) **Field of Classification Search**

(57) **CLAIM**

The ornamental design for a speaker with induction cell phone charger, as shown and described.

DESCRIPTION

FIG. 1 is a FRONT EXPLODED PERSPECTIVE view of a design for the speaker with induction cell phone charger; FIG. 2 is a FRONT ASSEMBLED PERSPECTIVE view of the speaker with induction cell phone charger; FIG. 3 is a TOP view thereof; FIG. 4 is a BOTTOM view of thereof; FIG. 5 is a FRONT view thereof; FIG. 6 is a BACK view thereof; FIG. 7 is a SIDE view thereof; and, FIG. 8 is an OPPOSITE SIDE view thereof.

The broken lines showing the bracket in FIG. 1 are for purposes of showing the relationship and order of assembly of various parts of the exploded view only and form no part of the claimed design.

1 Claim, 5 Drawing Sheets
